UNITED STATES PATENT OFFICE.

ARTHUR E. TRUESDELL, OF PITTSFIELD, MASSACHUSETTS, ASSIGNOR OF ONE-HALF TO DOHERTY RESEARCH COMPANY, OF NEW YORK, N. Y., A CORPORATION OF DELAWARE.

LIMEKILN AND METHOD OF BURNING LIME.

Application filed April 23, 1923. Serial No. 633,819.

This invention relates to the burning of lime and one of the objects of the invention is to provide a novel vertical lime kiln in which limestone can be successfully and efficiently burned with a fuel which develops a temperature in the products of combustion much higher than that which is suitable for burning lime, and another object of the invention is to provide a novel process of burning limestone by which fuel of this nature can be efficiently used.

5

10

For the most efficient burning of limestone it is desirable that the temperature of the 15 products of combustion to which the limestone is subjected should be adapted to the chemical composition of the limestone. Since such chemical composition varies 20 greatly in various limestones used for producing lime, especially in regard to the content of magnesium carbonate, there is considerable range in the proper temperature for burning various kinds of limestone. In no case however should the temperature of 25 the products of combustion be much higher than 900 degrees centigrade, at which temperature calcium carbonate is freely dissociated under atmospheric pressure.

The temperature of the products of combustion resulting from the burning of wood 30 as fuel is in the neighborhood of 1000 degrees centigrade and for this reason wood has been extensively used as the fuel for burning limestone in vertical kilns. Owing 35 to the present increasing scarcity of wood, however, other fuels for this purpose are in more or less demand, but one difficulty which arises when coal, oil or similar fuels are burned is that the products of combustion 40 produced by the burning of such fuel is much too high to produce a good quality of lime.

One method which has been heretofore suggested for reducing the temperature of 45 the products of combustion where coal is used for fuel has been to provide means for delaying the combustion by introducing waste kiln gases beneath the grate for the purpose of diluting the air used for producing combustion. While this method results in reducing the temperature of the products of combustion yet it has the disadvantage that it makes the combustion less efficient 50 with the result that the fuel is not burned 55 economically.

In my invention I have provided an apparatus and process by which fuel such as coal or oil can be burned in the most efficient manner while at the same time the products of combustion are delivered to the limestone 60 at the required temperature necessary for efficient burning of the lime.

I accomplish this end by burning the fuel in the most efficient manner with the result that products of combustion are developed 65 which are at a temperature in excess of that required for efficiently burning lime and then before introducing the high-temperature products of combustion into the vertical shaft of the kiln I reduce the temperature 70 of said products of combustion by diluting them with waste gases withdrawn from the kiln. These waste gases are, of course, relatively cool because of the heat which they have given up to the limestone in passing 75 through the kiln and the mingling of them in the proper proportion with the hot products of combustion serves to reduce the temperature of the latter to that which is desired for the most efficient burning of the 80 limestone.

One way of accomplishing this is by providing a recirculation fan which is constructed to withdraw the waste gases from the upper end of the shaft of the kiln and introduce them into the furnace beyond the point of combustion where they will commingle with the products of combustion before the latter are delivered to the shaft of 85 the lime kiln.

90 My process makes it possible to use successfully pulverized coal, oil or other similar fuels for the burning of limestone.

In order to give an understanding of the invention I have illustrated in the drawings 95 some selected embodiments of the invention which will now be described after which the novel features will be pointed out in the appended claims.

Fig. 1 is a vertical sectional view of a 100 lime kiln embodying my invention, said section being taken on the line 1-1, Fig. 2;

Fig. 2 is a side view of Fig. 1;

Fig. 3 is a top plan view;

Fig. 4 is a section on the line 4-4, Fig. 3; 105

Fig. 5 shows a different embodiment of the invention.

In the drawings 1 indicates the cupola portion of a vertical kiln which may be of any suitable construction and which is shown as 110

having at its upper end a filling hopper 2 through which the limestone is introduced and at its lower end a lime hopper 3 in which the burned lime gathers and from which it is removed.

Associated with the cupola are one or more furnaces 4 for producing the hot products of combustion delivered to the vertical cupola 1. These furnaces are of the type 10 adapted to burn coal, oil or other fuel, which when most efficiently burned produce products of combustion at a temperature considerably higher than that required for efficient burning of the limestone. The particular 15 furnace illustrated in the drawings is one designed to burn pulverized coal and it is provided with a combustion chamber 5 into which the pulverized coal is delivered under pressure through nozzle 6. The coal burns 20 as fast as it is delivered from the nozzles and the furnace is designed to admit the proper amount of air with the coal or otherwise so that complete combustion of the coal will take place in the chamber 5. The 25 products of combustion which are thus produced have a temperature of perhaps 1900 or 2000 degrees centigrade. This is much too high for the efficient burning of the limestone.

30 My invention contemplates the reducing of this excessively high temperature of the products of combustion by diluting them with waste gases withdrawn from the stack 1. This may be accomplished in various 35 ways. In Figs. 1 to 4 I have illustrated a recirculation fan 7 which is connected by an inlet duct 8 to the upper end of the cupola as shown at 9, the exhaust or discharge from the fan 7 delivering into a pipe 40 10 which is shown as provided with the two branches 11 that lead to two manifold chambers 12 one for each of the furnaces 4. Each chamber 12 is provided with ports 13 that open into the combustion chamber 5 in the 45 rear of the point of combustion. The fan 7, therefore, operates to withdraw waste gases from the top of the kiln 1 and to deliver said waste gases to the manifolds 12 from which they are delivered into the furnace 50 through the ports 13. Inasmuch as these ports 13 are situated back of the point where combustion takes place the waste gases will be commingled with the products of combustion but will not in any way interfere with 55 the combustion of the fuel. The waste gases which are withdrawn from the top of the kiln are, of course, at a relatively low temperature because of the heat which has been given up by them to the limestone during 60 their passage upwardly through the kiln. The commingling of these relatively cool gases with the excessively hot products of combustion reduces the temperature of the latter and by thus diluting the products of 65 combustion to the proper amount the tem-

perature thereof may be reduced to that which is most efficient for the burning of the limestone.

The fan 7 may be operated in any suitable way and by varying the speed at which the fan 70 operates or by the use of dampers the amount of waste gases delivered to the products of combustion can be varied and, therefore, the burned products of combustion can be brought to the right temperature for most 75 efficient burning of the limestone.

In Figs. 1 and 2 I have illustrated an exhaust fan 14 for withdrawing the gases from the kiln and producing proper draught therein and at 15 I have indicated a pyrometer by which the temperature of the waste gases can be determined. I have also shown a damper 31 in the pipe 10 for controlling the recirculation current. In the operation 80 of the device the exhaust fan may be run so as to produce the necessary draft through the kiln and the amount of recirculation of waste gases will be varied as necessary, to maintain the proper temperature in the kiln. If it is found that the temperature of the waste 85 gases delivered from the exhaust fan 14 is too high, thus indicating too high a temperature in the kiln, then the damper 31 may be opened to a greater extent so as to provide a greater amount of recirculation 90 of the waste gases and a greater dilution of the products of combustion. This will reduce the temperature of the products of combustion. On the other hand if it is found 95 that the temperature in the kiln is too low, thus indicating too great a dilution of the products of combustion then the damper 31 may be closed somewhat, thus reducing the amount of recirculation and the consequent 100 amount of dilution of the products of combustion. By thus regulating the amount of recirculation the temperature of the gases delivered to the limestone can be controlled 105 so as to produce most efficient burning of the limestone.

110 This same regulation of the temperature can also be secured by varying the relative speeds of the fans 7 and 14.

115 It will be noted that with this arrangement the fuel is burned so as to produce no complete combustion and thus a high degree of efficiency, but notwithstanding that burning of the fuel in this way produces products of combustion which have altogether too high a temperature for efficiently 120 burning the limestone, yet the efficient burning of the limestone is produced by this method of diluting the excessively hot products of combustion with cool waste gases from the kiln.

125 My invention, therefore, results in a high degree of efficiency in the burning of the fuel as well as a high degree of efficiency in the burning of the limestone.

130 In Fig. 5 a little different construction

is shown wherein a single fan is used for both recirculation and exhaust purposes. In this construction the single fan is indicated at 16, the inlet of the fan communicating with the upper end of the cupola 1 and the exhaust from the fan connecting with a pipe 17 which is branched, one branch 18 leading to the two branches 12 and the other branch 19 leading to the atmosphere. These two branches are provided with dampers 20 and 21 so that by regulating the dampers the proportion of the waste gases delivered to the furnaces relative to that which is delivered through the exhaust pipe 19 can be regulated thereby controlling the temperature of the gases which are delivered to the cupola.

While I have referred above to pulverized coal as fuel yet I wish it to be understood that the invention is not limited to any particular fuel, as oil may be used instead of pulverized coal or the furnace may be arranged to burn coal on a grate with just the right proportion of air to secure complete combustion. The invention contemplates the use of any fuel which when burned most efficiently produces products of combustion at a temperature in excess of that which is required for best operation of the lime kiln and the reduction of the temperature of such excessively hot products of combustion to that which is most efficient in burning the limestone by diluting such products of combustion with waste gases withdrawn from the kiln.

While, therefore, I have described some embodiments of the invention I do not wish to be limited to the constructional features shown. Furthermore I desire to state that while I have illustrated the invention as adapted to the burning of lime yet the invention is not necessarily confined to this use and may be used for other purposes.

I claim:

1. In a lime kiln a combination with the vertical kiln, of a furnace arranged to burn fuel under conditions to produce products of combustion at a temperature in excess of that required for the efficient burning of

limestone and to deliver such products of combustion to the kiln, and means to withdraw waste gases from the kiln and introduce them into the furnace between the point where the combustion takes place and where the products of combustion are delivered to the kiln.

2. The method of burning limestone in a kiln having a stack containing limestone and also having an external furnace, which consists in burning fuel in the furnace in such manner as to produce products of combustion at a temperature in excess of that required for the efficient burning of limestone, withdrawing waste gases from the top of the stack and commingling said gases with the products of combustion at a point beyond that at which said products of combustion are formed and before they are delivered to the stack, thereby to reduce the temperature of said products of combustion to that required for efficient burning of the limestone, and then introducing to the stack the commingled products of combustion and waste gases at the reduced temperature.

3. The method of burning limestone in a kiln having a stack containing limestone, which consists in burning fuel exterior to the stack under conditions to produce products of combustion at a temperature in excess of that required for the efficient burning of limestone, withdrawing from the top of the stack waste gases which have a temperature less than that required for the efficient burning of limestone, commingling said waste gases with the products of combustion exterior to the stack and at a point beyond that at which said products of combustion are formed, whereby the temperature of the products of combustion is reduced to that required for efficient burning of the limestone, and then introducing to the stack the commingled products of combustion and waste gases at the reduced temperature.

In testimony whereof, I have signed my name to this specification.

ARTHUR E. TRUESDELL.
